AUTOMATIC TELEPHONE SWITCH

Filed May 1, 1923

Inventor:
Oscar F. Forsberg,
Edward Adams,
Atty

UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed May 1, 1923. Serial No. 635,904.

To all whom it may concern:

Be it known that I, OSCAR F. FORSBERG, a citizen of the United States, residing at Yonkers, in the county of Westchester, State 5 of New York, have invented certain new and useful Improvements in Automatic Telephone Switches, of which the following is a full, clear, concise, and exact description.

This invention relates to automatic and 10 semi-automatic telephone switches. More particularly, it refers to improvements in switching devices of the type described in British Patent 183,438 to Western Electric Company, Limited, accepted September 6, 15 1923; wherein certain selecting and operating bars are provided for selectively operating a number of normally disengaged sets of active and passive contacts.

In switching devices of the type above 20 referred to, it is desirable to prevent the overthrow of the operating bars when actuated by their magnets, and to support them in adjusted position relative to their cooperating parts in case of the removal of their 25 electromagnetic operating means for adjustment or repairs.

The object of this invention, therefore, is to provide checking means whereby the angular distance of each operating bar is 30 limited in order to prevent damage which would otherwise occur due to the momentum imparted thereto by the energization of the operating magnets, and the utilization of said means for supporting the bars in adjusted position on the switch frame independently of their operating mechanism.

A feature of the invention resides in the provision of a stop plate whereby the stroke of the magnets may be adjusted independently and without disturbing the adjustment of the operating bars, and the provision of stopping and supporting members on said plate for arresting the operating bars and lifting fingers thereon in their operated 45 position, and for supporting the arms, connected with the armatures of the operating magnets, when said magnets are removed from the switch frame.

Other features of invention and advantages will appear from the following description, and by the claims appended thereto, reference being had to the accompanying drawings in which:

Fig. 1 is a top sectional view of said switch, Fig. 2 is a right-hand side view

thereof, Fig. 3 is a sectional view taken along line 3-3 of Figs. 1 and 2 looking in the direction of the arrows, showing the stop plate arranged on its supporting member, and Fig. 4 is a partial assembly view of a set of passive and active contacts showing a card and active contacts therein in normal non-operated position.

The switching structure shown in Figs. 1 and 2 generally comprises a plurality of 65 normally disengaged passive and active contact sets arranged in coordinate rows on insulating supports 10, 11, etc., arranged on the switch frame (not shown). Each active contact set generally comprises a number of wires 12, 13 and 14, associated with a corresponding number of contact wires 15, 16 and 17, which are preferably interwoven with a number of insulating weft bars 18 70 in the shape of a grid. For each active contact set 12, 13, 14, etc., there is provided an operating card 19 having obliquely disposed apertures 20, 21 and 22 shown in Fig. 4, in which the active contact wires protrude in juxtaposition with their associated grid wires 15, 16 and 17, respectively. The cards 19 are slidably arranged in channels formed by T-shaped bars 23 arranged on the supporting plate 24. The cards 19 are held in normal non-operated position by means of 75 retracting springs 25, which extend through apertures 26 in the lower end portion of the cards 19, and arranged to normally rest on the lower edges of windows 27 cut out of the supporting plate 24. 80

For each vertical row of active contacts there is provided a rotatable bar 28 on which a number of camming members 29 are securely arranged. On one end of each bar 28, there is provided a laterally extending 85 arm 30 which is disposed in operating relation with the arm 31 of an armature 31', adapted to rotate the bar 28 in response to each energization of electro-magnet 32.

For each set of grid wires 15, 16 and 17, there is provided a rotatable bar 33 carrying a number of pivotally arranged lifting fingers 34 which are each associated with a set of active contacts 12, 13 and 14 and a cam 29. The bars 33 are arranged by pairs and the bars of each pair are pivotally arranged on two supporting plates 35 held securely on upright supports such as 36 and 37 on two opposite sides of the switch frame. For the sake of clearness, however, only one plate 100 105 110

35 is shown in Fig. 1. On each supporting plate 35, there is fixedly arranged an operating electromagnet 40 and a pivotable armature 40' secured to an L-shaped arm 41 which normally rests on an adjustable support 42 of plate 35. An arm 43 is fixedly arranged on the bar 33 and extending therefrom across the arm 41 is held in operative relation thereon by means of a retractile 10 spring 44 hooked on the free end portion of arm 43 and on an adjustable arm 42'. A strip 45 is securely attached on the upright support 37 by means of a number of screws 46, 47, etc., and on it is provided a number 15 of stopping members 48, 49, etc. The stops 49 are adapted to support the bars 33 in adjusted position on the switch frame independently of their L-shaped operating arms 41, whereby the stroke of each magnet may 20 be adjusted independently of and without disturbing the adjustment of its associated operating bar. The stops 48 are each associated with a bar 33 and are adapted to limit the movement of the bars and lifting fingers 25 thereon in order to prevent them from crossing over their operating position when actuated by their operating magnets.

What is claimed is:

1. In a switching device, the combination 30 of an operating bar, an armature loosely connected therewith, a magnet for actuating said bar through a movement of said armature, a stop plate, and checking members thereon adapted to limit the movement of 35 said bar in two directions.

2. In a switching device, the combination 40 of a frame, a rotatable bar arranged thereon, a laterally extending arm secured on said bar, an armature in operating relation with said arm and loosely connected therewith, a magnet for actuating said bar through a

movement of said armature, and members on said frame for stopping said bar within a defined angular distance.

3. In a switching device, the combination 45 of a frame, a reciprocating bar arranged thereon, an arm carried by said bar, means for limiting the movement of said bar, independent of its actuating mechanism, said means comprising a plate attached to said frame, a stop thereon in the path of said arm to stop the bar at the end of its useful stroke, another stop for supporting said bar in normal non-operated position.

4. In a switching device, the combination 50 of a frame, a plurality of rotatable bars arranged thereon, a magnet armature associated with each of said bars, electromagnetic means for operating said armature, a stop plate arranged on said frame and common to 55 said bars, a plurality of laterally extending arms on said plate for preventing the overthrow of each of said bars when actuated by said magnets, and means on said plate for supporting said bars in their resetted position.

5. In a switching device, the combination 60 of a bar, an arm attached on one end of said bar, an armature in operating relation therewith, a magnet for operating said bar 70 through a movement of said armature, a stop plate disposed at right angles relative to said bar, a laterally extending arm thereon preventing the overthrow of said bar, an arm disposed at right angles to the first 75 mentioned arm for supporting said bar when its operating armature is removed from the switch frame.

In witness whereof, I hereunto subscribe my name this 28th day of April A. D., 1923.

OSCAR F. FORSBERG.
